CUPOLA FURNACE

Herman P. Kreulen, Elm Grove, Wis., assignor to
 Grede Foundries, Inc., Milwaukee, Wis., a corporation of Wisconsin

Application July 3, 1947, Serial No. 758,924

5 Claims. (Cl. 266—30)

1

This invention relates to improvements in cupola furnaces.

It is the object of the invention to reduce any tendency for bridging to occur in the cupola, to enable cupola operation at higher temperatures, to increase the melting capacity of a cupola of given size, to materially reduce the time required to knock out the slag, and to effect substantial savings of refractory material. The manner in which these objectives are achieved will appear more fully from the following disclosure of the invention.

In the drawings:

Fig. 1 is a view in side elevation of a cupola furnace embodying the invention.

Fig. 2 is an enlarged fragmentary detail view partially in side elevation and partially in section through the portion of the cupola with which the present invention is concerned.

Fig. 3 is a view taken in horizontal section on line 3—3 of Fig. 2.

Fig. 4 is a further enlarged detail view in perspective showing component parts of the tuyère.

The cupola shell 5 and its support on a base 6 carried by columns 7 are generally conventional. The base is provided with the usual bottom trap doors 8, shown closed in Fig. 2, and one of which is shown open in Fig. 1. Mounted on the shell is a conventional wind box 9 supplied with air under pressure by the usual blower (not shown). The windbox serves as a manifold to distribute the air to the various tuyère openings through the knees 10.

The interior of the shell has a refractory lining 11, through the lower portion of which opens the tap spout 12 and, at a slightly higher level, the slag spout 13. At a predetermined level, a few inches above the slag spout, are the tuyère blocks 15. These blocks are so flared as to increase in cross section in an inward direction. As shown in Fig. 4, the sides and bottom are preferably made integral, and the top segment 16 is separately fabricated. There is usually an intermediate baffle or partition 17. The tuyère blocks are symmetrically disposed, and the openings therethrough afford communication between the knees 10 and the interior of the cupola for delivering the blast to the charge.

Immediately above the tuyères, the lining is preferably increased in thickness or boshed at 18 to provide an overhang which tends to exclude both coke and slag from the tuyère openings. The boshed section is gradually tapered at 19 back to the original interior cross sectional dimension at 20.

2

The operation of my cupola follows generally the accepted practices. The trap doors 8 are closed and covered with a filling of dry sand to provide a bottom which drains toward the tap opening 12. Kindling on the sand is sufficient in amount and distribution to ignite the coke. About a third of the initial charge of coke is placed on the kindling and thoroughly ignited before the rest is added and before the blast is started. After the first batch of coke is thoroughly ignited, the second is introduced onto it, and when this is in full ignition, the third batch is added. Thereupon, the furnace is charged with iron and coke in the usual manner, and the blast is set in operation by supplying air under pressure to the windbox.

When the level of molten iron reaches a point where slag appears at the slag spout 13, the tap spout is opened, and the molten iron drained off until slag appears, whereupon it is again closed.

After all of the molten iron has been withdrawn at the conclusion of the heat, the trap doors 8 are opened to dump the residue of coke and slag. After the cupola is cool, and before any relining can be done, iron and slag adhering to the refractory lining must be broken out. In some instances, there is such adhesion of the slag and molten iron to the lining as to result in "hanging up," the entire mass bridging across the interior of the cupola and failing to discharge through the trap doors 8. The present invention minimizes adhesion of the iron or slag to the lining and substantially completely prevents hanging up, assuring a clean drop when the trap doors are opened. These results are brought about by using certain proportions which I have discovered.

In the past, there has been no recognized relationship between the tuyère size and the size of the cupola. The average cupola, regardless of size, has had tuyère openings which, as measured at the exterior shell, were about 5½ or 6 inches high, and of sufficient area to amount to a maximum of 25% of the horizontal cross section of the cupola. That is to say, the aggregate vertical cross sectional area of all of the tuyère openings totaled only a quarter the horizontal cross section of the cupola at the tuyère level.

I have discovered, and have demonstrated in actual commercial production, that remarkable and unexpected improvements in the functioning of the cupola are achievable provided the tuyère openings have an aggregate cross section of at least approximately $\frac{1}{3}$, and preferably at least

35% of the horizontal cross section of the cupola at tuyère level, and provided further that, regardless of cupola dimensions, the minimum height of the tuyère opening should be at least nine inches, and preferably approximately 11 inches. Both the specified height and the specified minimum cross section are essential. The results do not follow from the use of the specified minimum cross section unless the minimum height is as stated. Neither are the results obtainable in the use of the specified minimum height unless the area also bears the requisite relation to cupola cross section. Since the tuyères ordinarily flare inwardly, both the height and tuyère area referred to are ordinarily measured at the shell.

The possible variation in height is such that in small cupolas a height as low as 9 inches may be used successfully. A tuyère of less than 9 inches in height is not desirable, regardless of cupola size. While it is known that some tuyères have been as much as 9 inches, or even 11 inches, in height, there are none to my knowledge which have used heights of 9 to 11 inches or more in conjunction with an area of anywhere nearly $\frac{1}{3}$ that of the horizontal cross section of the cupola. Both the relative area and the height are required for the desired result.

There are many published recommendations as to the relative size of tuyère openings. I am familiar with a number of these, and they all recommend tuyère openings of a size very substantially smaller than that which I have found to give the unexpected results which are achieved through the use of my invention.

These results are believed to be attributable in part to the fact that the specified relative area of the tuyères is such as to reduce the velocity of the air blast at the tuyère openings. Where such velocity is high, the air tends to create and follow channels through the charge. In immediate proximity to the path of the air, the molten iron and slag are unduly cooled and caused to congeal and adhere to the fire brick or other refractory which lines the cupola. In aggravated cases, this results in bridging, which precludes the desired clean drop when the trap doors are opened. In all cases, the adhesion of the slag and iron to the fire brick increases the time required to clean out the cupola. It also results in injury to, or destruction of, the fire brick or other refractory material.

Where the specified dimensions and proportions are followed, bridging is so far reduced as to be substantially eliminated, even though the melting be conducted at higher temperatures with consequent increase in relative output. The melting capacity has been so greatly increased that it is common to find an increase of 15% in output as compared with the output of a cupola of the same size but with conventional tuyères.

The time required to "knock out" the material adhering to the fire brick has been reduced to half, or less than half, of the time required to "knock out" a conventional cupola of otherwise identical design. In many respects, the knock out time has been reduced to as low as $\frac{1}{5}$ of the time required to "knock out" the same identical cupola before the tuyères thereof were changed in accordance with the present invention.

Along with the saving in "knock out" time goes a substantially equivalent saving in fire brick or refractory lining material.

I claim:

- 5 1. A cupola having tuyère openings the minimum dimensions of which comprise a height of at least nine inches, and an aggregate cross section of at least one-third the area of the horizontal interior cross section of the cupola 10 at the level of the tuyère openings.
2. A cupola having a shell and a refractory lining, with tuyère openings through the shell and lining which flare inwardly and have a minimum opening adjacent the shell of eleven inches 15 in height, said tuyère openings having an aggregate area at their minimum cross section of at least one-third the cross sectional area of the interior of the cupola lining at the level of such openings.
3. A cupola having a shell and refractory lining and provided with tuyère openings through the shell and lining flaring inwardly from the shell, said openings having a minimum height of nine inches and a minimum aggregate cross 25 sectional area equal to at least 35% of the horizontal cross sectional area of the interior of the cupola lining at the level of such openings.
4. In a cupola having a shell, a windbox, and a refractory lining, a plurality of tuyère blocks 30 built into the lining and opening into the cupola and externally communicating with the windbox, each such block flaring inwardly from the shell and having a minimum height of eleven inches, the aggregate total cross section of the minimum 35 cross sectional areas of the openings through said blocks being at least thirty-five per cent of the total horizontal cross sectional area of the interior of the cupola lining at the level of such openings.
5. In a cupola furnace comprising a support provided with trap doors, a shell upstanding on said support, a windbox encircling the shell, knees leading from the windbox and a refractory lining for the shell, the lining and shell having 45 tuyère openings with which said knees communicate, the combination of tuyère blocks extending through the lining from the shell, said lining having an overhang above the blocks, the blocks having a minimum height in excess of nine 50 inches and an aggregate minimum cross sectional area at the shell totalling at least one-third of the horizontal cross sectional area of the cupola at the level of said openings.
